DESIGN FOR A RING OR THE LIKE

Frank Milhening, Evanston, Ill., assignor to J. Milhening, Inc., Chicago, Ill., a corporation of Illinois

Application October 26, 1938, Serial No. 80,688

Term of patent 7 years

To all whom it may concern:

Be it known that I, Frank Milhening, a citizen of the United States, residing at Evanston, in the county of Cook and State of Illinois, have invented a new, original, and ornamental Design for a Ring or the like, of which the following is a specification, reference being had to the accompanying drawing, forming a part thereof.

In the drawing:

I claim:

The ornamental design for a ring or the like, substantially as shown.

FRANK MILHENING.
